The ornamental design for a disc brake rotor, as shown and described.

DESCRIPTION

FIG. 1 is a rear perspective view of the disc brake rotor;
 FIG. 2 is a front perspective view thereof;
 FIG. 3 is a left side elevation view thereof; the right side elevation view is identical thereto;
 FIG. 4 is a front plan view thereof;
 FIG. 5 is a rear plan view thereof; and,
 FIG. 6 is a cross-sectional view taken along line 6-6 in FIG. 4. The broken line showing of the five wheel studs is provided for the purpose of illustrating environmental structure and forms no part of the claimed design.
